UNITED STATES PATENT OFFICE.

CHARLES C. KOPLIN, OF BARTLESVILLE, OKLAHOMA.

SUSPENDED PUMPING POWER.

1,370,594.

Specification of Letters Patent.

Patented Mar. 8, 1921.

Application filed July 6, 1920. Serial No. 394,273.

To all whom it may concern:

Be it known that I, CHARLES C. KOPLIN, a citizen of the United States, residing in the city of Bartlesville and State of Oklahoma, have invented new and useful Improvements in Suspended Pumping Powers, of which the following is a specification, reference being had to the accompanying drawings.

The present invention pertains to pumping powers for use in oil fields for the purpose of pumping oil from the wells, or for like purposes. The pumping unit as now employed comprises a master wheel with its axle and upon the axle is rigidly mounted a circular cam provided with a sliding yoke upon its outer periphery, to which yoke may be attached any number of pull rods. The ends of these pull rods are then extended and attached to the pumps in the field. In this way a large number of scattered pumps may be operated from one pumping unit.

The primary purpose of the present invention is to provide an improved form of construction for such pumping unit which may be called a suspended pumping power, wherein two eccentrically mounted yokes are mounted upon one master wheel and are pierced with holes around their outer peripheries as means for attaching the pull rods.

A further object is to provide a mechanism of the class described having facilities for operating a greater number of pumps than can be operated with the ordinary pumping unit.

A further object is to provide a mechanism of this character constructed in a simple, practical and efficient form best adapted to carry out the purposes intended.

In the drawings as embodying the preferred form of construction of this invention—

Figure 1 is a frontal elevation showing my improvement as set up and in operation.

Fig. 2 is a top plan view.

Fig. 3 is a side elevation.

Referring more particularly to the drawings, my invention consists of the large annular track ring 1, around the inner periphery of which are journaled a plurality of flanged rollers 2. Within the flanges of these rollers is rotatively mounted the master wheel 3. Around and upon the under side of this wheel 3 is rigidly mounted the beveled circular rack 4, adapted to mesh with the pinion 5. The pinion 5 is rigidly

mounted at the inner end of the shaft 6, which shaft is journaled in the frame at 7 and is provided at the outer end with the rigidly mounted power wheel 8. The apparatus as so far described is horizontally mounted upon the frame 9. Upon the upper face of the master wheel 3 is rigidly mounted the primary crank head 10, eccentrically of the axis of the master wheel 3. This crank head 10 is provided with a groove 11 within which is rotatively mounted the annular yoke 12. Upon the crown of the crank head 10 and so as to clear the yoke 12 is rigidly mounted the horizontal crank arm 13, same being extended directly across the central axis of the master wheel 3, and upon the outer end of this crank arm is rigidly mounted another or secondary crank head 14, same being likewise eccentrically located relative to the axis of said master wheel. Upon this secondary crank head 14 is rotatively mounted the secondary yoke 15. Both the primary yoke 12 and the secondary yoke 15 are pierced with a plurality of pull rod holes as shown at 16 and 17, same being adapted to receive the inner ends of the pull rods 18 and 19, the outer ends thereof being extended to the pumps for the purpose of operating the same.

It is obvious that as the power wheel 8 rotates the pinion 5, the master wheel 3 is caused to revolve within the rollers 2, thus causing the yokes 12 and 15 to move eccentrically around the axis of the master wheel 3, and causing the pull rods 18 and 19 to oscillate backwardly and forwardly, for the purpose of operating the pumps.

While I have herein described a certain specific method of constructing and assembling the elements of my invention, it is understood same may be varied in minor details, not departing from the spirit of my invention as defined in the appended claim.

What I claim to be new and patentable is:

A mechanism of the character described, comprising a supporting frame; a shaft horizontally journaled in the frame; a power wheel rigidly mounted at the outer end of the shaft; a pinion rigidly mounted at the inner end of the shaft; a track ring rigidly and horizontally mounted on the frame above the pinion; a plurality of flanged rollers mounted around the inner periphery of the track ring; a master wheel rotatively mounted within the track ring and supported by said rollers as bearings; a cir-

cular rack rigidly mounted around the underside of the track ring, in mesh with said pinion; a primary crank head rigidly mounted upon the upper side of the master wheel, eccentrically of the axis thereof; a crank arm rigidly and horizontally mounted upon said primary crank head and extended across and beyond the axis of said master wheel; a secondary crank head rigidly mounted at the end of said crank arm, ec-

centrically of the axis of the master wheel; yokes rotatively mounted upon said primary and secondary crank heads; and pull rod holes pierced through the said yokes, as means for attaching the pull rods extended to the pumps.

CHARLES C. KOPLIN.
